UNITED STATES PATENT OFFICE

116,138

DESIGN FOR A CYCLE SADDLE SEAT

Harold E. Kalter, Elyria, Ohio, assignor to The
Troxel Manufacturing Company, Elyria, Ohio,
a corporation of Ohio

Application February 27, 1939, Serial No. 83,220

Term of patent 7 years

To all whom it may concern:

Be it known that I, Harold E. Kalter, a citizen of the United States, residing at Elyria, in the county of Lorain and State of Ohio, have invented a new, original, and ornamental Design for a Cycle Saddle Seat, of which the following is a specification, reference being had to the accompanying drawing, forming a part thereof, in which;

Fig. 1 is a side elevational view of a cycle saddle seat, showing my new design; and Fig. 2 is a rear elevational view thereof. The characteristic features of my design reside in the portions shown in full lines.

I claim:

The ornamental design for a cycle saddle seat, substantially as shown, and described.

HAROLD E. KALTER.
